GARMENT FORM

Edythe Drage Browne, Chicago, Ill.

Application July 28, 1938, Serial No. 221,761

5 Claims. (Cl. 223—68)

My invention relates, generally to forms for fitting dresses and other garments, and has particular relation to a laminated garment form of coherent structure which is formed upon the body of the person whose figure is to be reproduced, in a manner to provide an accurate reproduction of the individual anatomical structure of the figure, and which will retain its shape upon removal from the figure so that it may be used as a form upon which dresses or other garments may be fitted, thereby eliminating the necessity of fitting the garments directly upon the person.

My invention consists in first applying a foundation garment to the body and particularly to the torso of the person, and then applying and molding shaped adhesive sections to the foundation garment accurately to define the distinctive figure conformation. The accurate form thus provided is then cut and removed from the figure and will retain its shape upon removal.

The foundation garment and shaped adhesive sections constitute the main pieces for producing the form of my invention, and these pieces are preferably made up in different sizes, making it possible, for example, for a woman with a size 36 figure, by purchasing form pieces of that size, to obtain general conformity to her figure. In actual practice, I contemplate making the form pieces in different standard sizes, such as large, medium, and small. Then as the form pieces are applied, they are hand-molded or shaped to define accurately the distinctive figure conformation.

The shaped character and size of the adhesive sections permit these sections to be applied accurately and expeditiously and with a minimum of help, and without requiring the person to stand in fitting position for an unduly long period of time. Better conformation to the figure is also obtained by reason of the shaped character of the adhesive sections.

Another feature of my invention consists in the provision of reenforcing or stiffening pieces which coact with the shaped adhesive sections to give the form the desired degree of stiffness and rigidity whereby it will accurately maintain its shape after removal and will not be distorted in fitting garments thereon.

Further features and advantages of my invention will be apparent from the following detailed description, taken in connection with the accompanying drawings in which:

Figure 1 is an elevational view of the foundation garment of my improved form;

Figure 2 illustrates collectively some of the shaped adhesive sections of one embodiment of my invention;

Figure 3 illustrates collectively other shaped adhesive sections;

Figures 4, 5, 6, 7 and 8 illustrate further shaped adhesive sections for use with the sections shown in Figures 2 and 3;

Figure 9 is a back view of the figure of a woman, showing the manner of applying the form;

Figure 10 is a front view of the figure of a woman showing the form applied thereto;

Figure 11 is a perspective view of the form after removal from the body of the person whose figure is reproduced by the form;

Figure 12 is a fragmentary front view of one of the stiffening or reenforcing pieces; and

Figure 13 is a fragmentary side view of the stiffening or reenforcing piece shown in Figure 12.

In carrying out my invention, I employ a foundation garment 10 to serve as a base and shaped adhesive sections of suitable fabric, preferably paper, to give a certain degree of stiffness and rigidity to the form, whereby it will maintain its shape upon removal from the body of the person.

The foundation garment 10 is preferably formed of knitted material, although it may, within the scope of the present invention, be formed of any other suitable textile material, or of paper. This garment 10 has a standing collar 11, and is made up for distribution in different sizes along with a set of shaped adhesive sections of corresponding size.

Common brown kraft paper, gummed on one side, is one suitable material of which the shaped sections may be formed. The particular foundation garment and shaped sections shown in the drawings are for making a dress form. In the illustrated embodiment of the invention, the shaped sections for this particular form comprise a front center section 12, two front side sections, one of which is shown at 13, a back center section 14, two back side sections, one of which is shown at 15, a collar section 16, back yoke section 17, front yoke section 18, belt sections 19 and 20, two belt sections, one of which is shown at 21, a back skirt section 22, front skirt section 23, two side skirt sections, one of which is shown at 24, and two underarm sections, one of which is shown at 25.

It is to be understood that the particular number and shapes of the sections shown in the drawings are illustrative and not limiting. Any

other desired number of such sections may be employed, and the particular shapes of said sections may vary. The particular sections illustrated are of the general character of the sectionalized paper garment patterns for use in shaping garments, as well understood in the art, except that instead of being used flat to enable cutting the sections of the garment to the desired shape and size, they are gummed or provided with adhesive and applied to the foundation garment while the same is in place on the body of the person whose figure is to be reproduced, and, with the foundation garment, constitute the essentials of a fitting form which is an accurate reproduction of the figure and retains the shape given it for use in fitting garments thereon.

In making up the form, the foundation garment is first placed upon the body of the person whose figure is to be reproduced and pulled down to smooth out any wrinkles. From underneath, it is firmly pinned to the garters. Reinforcing or stiffening strips 30 are then attached to the garment 10. The strips 30 are in the form of relatively narrow strips of metal or other suitable material, having prongs or other suitable attachment elements 32 struck out therefrom. The attachment elements 32 are flattened and engaged downwardly with the foundation garment 10 so as to catch slightly into the material of this garment and attach the stiffening strips in place.

In the illustrated embodiment of the invention, I employ six reinforcing or stiffening strips 30, one extending up to the underarm at each side, and two at the front, and two at the back. This particular number of stiffening strips, as shown in the drawings, is illustrative and not limiting, it being understood that any other desired number and arrangement of these strips 30 may be employed within the scope of the present invention.

After the strips 30 are fastened in place, the shaped adhesive sections are applied to the foundation garment 10 over this garment and over the strips 30 while the foundation garment is in place on the body of the person. This is accomplished by moistening the entire gummed or adhesive surfaces of the respective shaped sections—for example, with a wet sponge—and applying the moistened gummed surfaces to the foundation with the shaped sections in their appropriate positions. The adhesive sections preferably overlap, completely to cover the foundation garment and to provide the desired stiffness and rigidity. The particular order in which the shaped sections are applied may vary. One suitable order of application is to apply the side front, side back, center front and center back sections, followed by the collar section 16, the ends of which overlap at the back, whereas the tabs 36 are secured by the adhesive thereon to the upper ends of adjacent sections.

The front yoke and back yoke sections and the underbust and underarm sections are then similarly applied. A piece of string or the like may be applied around the waist and tied in place, whereupon the skirt sections and belt pieces are applied. In applying the shaped sections, they are hand molded or shaped with the hands to the adjacent portions of the body to define accurately the distinctive figure conformation and produce an exact reproduction of the figure of the person on whom the model is formed. The shaped character of the adhesive

sections makes it possible to apply the same accurately and expeditiously and with a minimum of help, and without requiring the person to stand in fitting position for an unduly long period of time. Moreover, the shaped character of these sections cooperates with the other features to provide a perfect fitting form.

As the moistened adhesive surfaces of the shaped sections dry after their application to the foundation garment, the form stiffens and becomes an accurate reproduction of the figure of the person, which retains its shape upon removal from the figure so that it may be used as a form upon which dresses or other garments may be fitted.

After the material is shaped to form and dried and set as above described, the form is cut or slit, preferably up the back, as indicated by the dot and dash line 40 in Figure 9, and up the center of the front, as indicated by the dot and dash line 41 in Figure 10, and removed from the person. An old corset steel or other piece of flexible metal may be slipped between the form and undergarments to facilitate cutting, which may be done with a scissors. Upon removing the two sections of the form, these sections are placed with the edges together and are joined and the slits closed by gummed paper or other adhesive strips as indicated, for example, at 42. The form may then be placed on a coat hanger or other suitable support, and serves as a fitting form upon which a dress or other garment may be accurately fitted to the exact figure conformation of the person on whom the form was made. If desired, the strips which join the two sections of the form may be joined at one end or along one side to the form before slitting and removing the same from the figure, and then when the two sections are placed with their edges together, the other ends or other sides of the adhesive strips may be moistened and joined to the other form section. The pasters or adhesive pieces are permitted to dry and other pasters, such, for example, as vertical adhesive strips 50 (Figure 11) or other cross strips similar to strips 42, are applied until the closing is complete.

If desired, the person applying or assisting in the application of the form, may take the measurements of the person to whom the form is applied before making the application, and after the form is completed, the measurements of the form may be taken and compared with the first-mentioned measurements.

The present form is inexpensive, relatively simple, light weight, and easily portable, and it provides a true and reliable lay figure over which garments may be satisfactorily fitted.

I do not intend to be limited to the precise details shown or described, and it is to be understood that the garment form of my invention may be used for fitting men's, women's, and children's garments, or for fitting surgical appliances, or elsewhere as desired.

I claim:

1. A garment form comprising, a foundation garment generally of a shape and size to fit the torso of a person and adapted to be placed thereon, and a plurality of adhesive sections formed to a pattern generally corresponding with the size of the person, each section being of different shape and conforming generally in contour with a correspondingly shaped portion only of the body of the person, said sections being adapted to be applied to said foundation garment while

same is in place upon the person, said shaped adhesive sections adapted to be hand-molded to define accurately the distinctive figure conformation of the torso and of a character to impart stiffness and rigidity to the form whereby it will retain its shape for fitting garments thereon when removed from the person.

2. A garment form comprising, a foundation garment generally of a shape and size to fit the 10 torso of a person and adapted to be placed thereon, stiffening means adapted for attachment to the outer surface of said foundation garment, and a plurality of shaped adhesive sections formed to a pattern generally corresponding with 15 the size of the person, said sections comprising individual back, front and side sections conforming generally in contour with corresponding portions only of the body of the person and of a size to substantially entirely cover such portions, 20 said sections being adapted to be applied as a covering over the outer surface of said foundation garment and in covering relation over said stiffening means while the foundation garment is in place on the person, said shaped adhesive 25 sections adapted to be hand-molded to define accurately the distinctive figure conformation of the torso and of a character to impart, in conjunction with said stiffening means, stiffness and rigidity to the form whereby it will retain its 30 shape for fitting garments thereon when removed from the person.

3. A garment form comprising, a textile foundation garment generally of a shape and size to fit the torso of a person and adapted to be placed thereon, said foundation garment having an upstanding collar, a plurality of upright stiffening stays having prongs for attachment of said stays to the outer surface of the foundation garment in generally upright position, and a plurality of adhesive paper sections, each section being of different shape and conforming in contour with a correspondingly shaped portion only of the body of the person, the sections collectively having the general shape of the person, 45 said sections being adapted to be applied as a covering over the outer surface of said founda-

tion garment and in covering relation over said stiffening stays while the foundation garment is in place on the person, said shaped adhesive paper sections adapted to be hand-molded to define accurately the distinctive figure conformation of the torso and of a character to impart in conjunction with said stiffening stays stiffness and rigidity to the form whereby it will retain its shape for fitting garments thereon when removed from the person.

4. A method of forming a garment form, which consists in first cutting a plurality of adhesive sections to different shapes, each section generally conforming in contour with a correspondingly shaped portion only of the torso of the body 15 of a person, covering the torso of the body of a person with a foundation garment, applying to said foundation garment while same is on the person the plurality of shaped adhesive sections, said sections being of a character to impart stiffness and rigidity to the form, cutting the form from top to bottom and removing it from the person and connecting the edges of the form along the cut to form an integral form for fitting garments thereon.

5. A method of forming a garment form, which consists in first cutting a plurality of adhesive sections to different shapes, each section conforming generally in contour with a correspondingly shaped portion only of the torso of the 30 body of a person, covering the torso of the body of a person with a foundation garment, attaching a plurality of upright stiffening stays to the outer surface of said foundation garment in generally upright position, applying to said foundation garment and over said stiffening stays while the foundation garment is on the person the plurality of shaped adhesive sections, said sections being of a character to impart stiffness and rigidity to the form, cutting the form from 35 top to bottom and removing it from the person, and connecting the edges of the form along the cut to form an integral form for fitting garments thereon.
